REFRIGERATING APPARATUS

George D. Reinhardt, San Antonio, Tex.

Application July 31, 1936, Serial No. 93,701

3 Claims. (Cl. 62—126)

This invention relates to refrigerating apparatus.

The main object of the invention is to secure higher efficiency in refrigerating effect with minimum evaporating surface and a material reduction in the required motor power and compressor capacity.

Another object is to prevent pre-expansion and wasted evaporation of the liquid refrigerant whereby to make available for useful work all vaporization of the liquid.

A further object of the invention is to increase the velocity of the refrigerant at the lower temperature in the enclosed evaporator space whereby to gain in heat transfer.

A still further object is to produce a positive flow of the refrigerant in the evaporator coil by means of an ejector issuing from a high-pressure fluid coil through an interposed nozzle.

20 A construction designed to carry out the invention will be hereinafter described, together with other features of the invention.

The invention will be more readily understood from a reading of the following specification and 25 by reference to the accompanying drawing, in which an example of the invention is shown, and wherein:

Figure 1 illustrates a schematic general assembly of accumulator unit and evaporator coil system and the directly correlated parts of the apparatus;

Figure 2 is a view, on an enlarged scale, showing the lower portion of the accumulator shell in section and details of the ejector valve and communicating connections between the accumulator unit and the evaporator coil; and

Figure 3 is a cross section through the ejector nozzle and valve cylinder.

Referring to the drawing, the numeral 10 indicates a main header pipe or manifold constituting a part of the evaporator unit or coil of the apparatus, said pipe or manifold 10 having an inlet pipe 2 at one end and a series of riser pipes or branches 11 leading from its opposite end and 45 converging together into a header pipe or manifold 3. The pipes 11 may be formed and arranged in any convenient shape that will facilitate the flow of the refrigerant therein, whereby to prevent pockets or traps where liquid might accumulate and also to facilitate the heat transfer between the confined refrigerant within the evaporator unit and the medium surrounding the unit.

Interposed between the inlet pipe 2 and the outlet header or manifold 3 of the evaporator unit

is a hollow drum 4 of a size several diameters larger than the header or manifold 3 and of such cubical dimensions as to permit proper separation of the liquid and vapors entering the drum through said header or manifold 3. An outlet pipe 5 leads from the upper portion of the drum 4 to the inlet of a compressor (not shown) whereby suction is created in said pipe 5 to draw the spent vapor or gas from the evaporator.

Within the hollow accumulator shell or drum 4 is a helically wound cylindrical pipe coil 8 whose upper or inlet end portion extends out through an opening in the shell or drum and is connected to a throttling device or control valve 7, from the opposite side of which latter a pipe 6 leads to a 15 reservoir or a receiver of the liquid refrigerant (not shown).

The lower or outlet end portion of the pipe coil 8, as shown, is screw-threaded and connected to a coupling member or thimble 9, which in turn is connected to a nozzle member or ejector 13 having a constricted passage 14 therethrough for a portion of its length, beyond which is a flared or divergent throat or outlet passage 15, said constricted passage 14 and flared passage 15 being 25 in axial alignment with each other and the passage 14 communicating with the lower end of the pipe coil 8 through the coupling thimble 9.

Surrounding the nozzle member or ejector 13 is a hollow cylindrical member 16 whose upper end is closed by a wall, except for an axial opening in said wall, through which the nozzle member or ejector 13 is inserted. As shown, the nozzle member is provided with an annular shoulder 13' which rests on the end wall of said cylindrical member 16, whereby to support the pipe coil 8. In this connection, it may be here noted that the nozzle member or ejector 13 need not necessarily be secured in the end wall opening of the cylinder 16 with a relatively tight or sealed fit but 30 need only be inserted loosely therein with the shouldered portion 13' resting on the end wall of said cylinder 16.

The lower end of the cylinder 16 is open and, as shown, has a screw-threaded attachment to a coupling member or thimble 19 whose lower end portion has a screw-threaded attachment with the upper end portion of the inlet pipe 2 of the evaporator unit, which pipe extends up into the lower portion of the accumulator drum or shell 4, the pipe being welded or otherwise secured to the bottom of the shell or drum 4 with a leak-tight jointure.

Preferably, the upper end portion of the nozzle member or ejector 13 is provided with a counter-

bore 12 in which is placed a filtering screen or element through which the liquid from the pipe coil 8 passes before it enters the restricted bore 14 of said nozzle member or ejector 13. The cylinder 16 surrounding the nozzle member or ejector 13 is provided with a series of apertures 18 through which communication is established between the interior of said cylinder 16 and the surrounding space in the lower portion of the accumulator drum or shell 4.

In the operation of the apparatus shown in the drawing, the liquid refrigerant, for example, ammonia liquid, is passed under pressure from the reservoir or receiver (not shown) through the pipe 6 and controlling valve 7, into the pipe coil 8. From the coil 8 the liquid under pressure is forced through the restricted passage 14 of the nozzle member or ejector 13, whence it is delivered into the divergent or flared passage 15 of the nozzle member or ejector 13, by the provision of which the liquid expands into the pipe 2 which is of somewhat larger diameter than the coiled piping thereby reducing the pressure but increasing the velocity of the fluid.

25 Obviously, as the liquid expands in the pipe 2 evaporation occurs, whereby the header or manifold 10 and evaporator coil pipes 11 become filled with the expanded and vaporized ammonia liquid, that is to say, the header or manifold and coil 30 pipes are filled with a mixture of ammonia liquid and gas, obviously under relatively low pressure. In other words, the evaporator is operated in "flooded" condition, as it is termed in this particular art.

35 The expanded liquid and the vapor or gas therefrom in the evaporator pipes boils over and into the accumulator shell or drum 4, through the header or manifold 3. Being in the form of liquid and gas, the liquid portion of the refrigerant entering the accumulator shell or drum 4 drops to the bottom of the latter while the lighter gas is drawn off from the shell or drum 4 through the pipe 5 by the suction of the compressor.

Any entrained moisture in the boiled over refrigerant within the shell or drum 4, upon coming in contact with the coil 8 which naturally is heated by the compressed high pressure liquid therein, gives up its latent heat and is re-evaporated and turned into gas. This produces a dry 50 saturated gas which has the effect of cooling the coil 8 and the liquid therein before the gas is drawn into the pipe 5 by the suction of the compressor. Any liquid not re-evaporated falls to the bottom of the accumulator and is drawn back 55 into the evaporator coil, through the apertures 18 in the cylinder member or aspirator tube 16, by the suction produced by the jet from the nozzle member or ejector 13, whence it is circulated with the liquid from the nozzle member or ejector 13 60 through the evaporator coil or piping.

Positive flow of the low pressure refrigerant in the evaporator coil or piping is produced by the liquid jet from the high-pressure coil, as just above noted, said jet producing a high velocity of 65 the liquid when leaving the nozzle and forcing all liquid ahead of it into the evaporator, which, obviously, is at a relatively low pressure.

In a flooded type evaporator coil the entire coil, as herein above noted, is filled with low-pressure 70 refrigerant, which, obviously, is boiling due to the heat being absorbed from the surrounding medium, which, for example, may be water, brine or other media. Gain in heat transfer is accomplished due to the fact that the refrigerant flowing at high velocity through the evaporating coil

5 prevents formation of large bubbles so that the liquid refrigerant moves in intimate contact with the inner surface of the tubing and takes up the heat more rapidly from the medium surrounding the coil and in contact therewith on the outside. 10 The advantage of an arrangement of apparatus in accordance with the present invention is that a small amount of evaporating surface per pound of refrigerant used is provided and at the same time it makes for smaller and more compact machines and coolers, as well as reducing the required motor power and compressor capacity.

What I claim and desire to secure by Letters Patent, is:

1. In a refrigerating apparatus, an accumulator 15 comprising a closed vertical hollow shell and a vertical pipe coil therein, said shell having an outlet leading from its upper portion to the suction side of a compressor, a manifold located below said accumulator shell, a pipe connected communicably at one end to the inlet end of said manifold and having its opposite end portion extended vertically into the lower portion of said accumulator shell, an annularly apertured tubular aspirator member disposed vertically within 20 the shell, said aspirator member being connected communicably at its lower end with said manifold-connecting pipe and having an axial opening in its upper end, a vertical nozzle member inserted in said aspirator member through the upper end opening of the latter, said nozzle member being connected to the lower end of said pipe coil within said shell and having a downwardly flared throat and a restricted axial passageway 25 between the throat and said pipe coil, the throat outlet of the nozzle member being located below the apertured portion of the aspirator member, evaporator tubing connected at one end to the outlet end of said manifold, and another manifold connecting the opposite end of said evaporator tubing communicably with the interior of 30 said accumulator shell intermediate the ends of the latter.

2. In a refrigerating apparatus, an accumulator shell having a communicable connection with the outlet of an evaporator whereby to receive the overflow of refrigerant from the evaporator, the liquid separated from the vapor in the overflow precipitating and accumulating in the lower portion of the shell and the vapor being withdrawn 45 from the upper portion of the shell, a pipe leading from the bottom of the shell to the refrigerant inlet of the evaporator, said pipe extending vertically into the shell, an aspirator tube communicably attached at its lower end to said pipe within said shell, said aspirator tube having an annular series of apertures therein but being otherwise closed, a nozzle member extending 50 downward axially in said aspirator tube with its lower end below the annular series of apertures 55 of said tube, said nozzle member having an axial passageway therethrough, the upper portion of which is restricted and the lower portion flared 60 downwardly to the lower end of the member, and a supply pipe from a source of liquid refrigerant 65 under high pressure extending downwardly in said accumulator shell and communicably connected at its lower end to the upper end of said nozzle member.

3. In a refrigerating apparatus, an accumulator 70 shell connected at its upper portion to an evaporator to receive the refrigerant overflow from the evaporator, the liquid separation of the overflow precipitating and accumulating in said shell, a pipe leading from the bottom of said accumulator 75

shell to the refrigerant inlet of the evaporator, said pipe extending vertically into the lower part of the shell and having a vertically disposed annularly apertured aspirator tube coupled axially to its upper end, and a supply pipe from a source of liquid refrigerant under high pressure extending through said shell and having a nozzle member directed vertically downward axially in said

aspirator tube with its lower end terminating below the annular series of apertures of said aspirator tube, said nozzle member having an axial passageway therethrough, the upper portion of which is restricted and the lower portion flaring 5 downwardly to the end of the member.

GEORGE D. REINHARDT.
